UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER,
ENGLAND.

TRUNNION-BLOCKS OF GUN-MOUNTINGS.

1,171,099.

Specification of Letters Patent.

Patented Feb. 8, 1916.

Application filed August 17, 1912. Serial No. 715,583.

To all whom it may concern:

Be it known that we, ARTHUR TREVOR DAWSON, knight, and GEORGE THOMAS BUCKHAM, both subjects of the King of 5 Great Britain, residing at Vickers House, Broadway, Westminster, in the county of London, England, have invented certain new and useful Improvements in or Relating to the Trunnion-Blocks of Gun-Mountings, 10 of which the following is a specification.

This invention relates to trunnion blocks for use with gun mountings (particularly pedestal mountings) in which the gun and 15 its cradle are adapted to be drawn in a rearward direction when it is desired to bring the trunnion blocks out of their recesses in the side cheeks of the carriage for the purpose of housing the gun.

According to our invention we provide 20 each of the trunnion blocks with a locking member which is situated in front of the trunnions instead of to the rear as heretofore, and which is adapted to be actuated, 25 either directly or through gearing, by a handle that moves the locking member into or out of engagement with a part of the carriage. The recess in the side cheek of the carriage with which the front portion of 30 the trunnion block engages is so formed that the said block is surrounded by the metal of the carriage cheek, and the locking member is carried in a transverse gap in the trunnion block in such a manner that it can engage 35 with the carriage cheek in two places. By these means the necessary resisting surface and strength of the locking blocks is obtained by one member and the carriage can also be made much shorter at the front.

The said handle may, as has heretofore been 40 proposed, be so constructed that it cannot be removed unless the locking member is in the locking position and is so arranged that when the locking member is in the unlocked 45 position the sight is prevented from being placed in its holder; thus the gun cannot be sighted and fired before the trunnion blocks are locked to the side cheeks of the carriage.

Each of the trunnion blocks may be furnished 50 with a bush in which the trunnion is eccentrically mounted, so that by altering

the position of each of the bushes in the trunnion blocks the trunnions can be adjusted as regards the distance of their axes 55 from the axis of the center pivot about which the gun moves in training, for the purpose of balancing the total load about the pivot as would be required in such circumstances for example as the removal or 60 addition of a shield.

In order that our said invention may be clearly understood and readily carried into effect we will describe the same more fully with reference to the accompanying drawings in which:

Figure 1 is a longitudinal vertical section showing a trunnion block, furnished with our improvements, in position in the recess provided for it in the cheeks of the carriage. 70 Fig. 2 is a transverse section taken approximately on the line 1, 1 of Fig. 1. Fig. 3 is a transverse section taken approximately on the line 2, 2 of Fig. 1, the locking member for the trunnion block being shown in the 75 locked position. Fig. 4 is a view similar to Fig. 3 showing the locking member in the unlocked position, and Fig. 5 is a horizontal section taken approximately on the line 3, 3 of Fig. 1. Fig. 6 is a side elevation, and 80 Fig. 7 a plan showing the manner in which the sight is prevented from being placed in its holder when the actuating handle of the locking member is in place, and the locking member is in the unlocked condition. 85

In these figures, A is one of the side cheeks of the gun carriage, B the cradle and C one of the trunnions.

D represents one of the trunnion blocks and D' the bush in which the trunnion is 90 eccentrically mounted.

E represents the locking member and E^x its actuating handle.

The locking member E is in the example shown in the form of a disk with two flattened parallel portions on either side of its center, the width of the member at this point being slightly less than the width of the trunnion block D and consequently than that of the trunnion block recess into which the front end of the trunnion block fits. The locking member E is disposed within a transverse gap e in the said front end of the trunnion block and is rigidly mounted on a

spindle e' , carried longitudinally in the said block. The walls of the carriage cheek are formed with vertical slots a , a which, when the trunnion block is in its foremost position, lie opposite the locking member E , so that when the latter is in the horizontal or locking position shown in Figs. 1 to 3 its ends engage in the slots a , a and prevents the trunnion block D from being displaced. When the locking member is in the vertical position shown in Fig. 4, its ends are removed from engagement with the slots a , a and it is then in the unlocked condition so that the cradle together with the gun can be withdrawn in the direction indicated by the arrow in Fig. 1. The spindle carrying the locking member E is provided at its rear end with a bevel segment e^2 (Fig. 5) gearing with a bevel pinion e^{2x} on a transverse spindle e'^x carried by a bracket D^x connected to the trunnion block D . The outer end of the said spindle is made hexagonal to receive a similarly shaped socket e^x on the shank of the actuating handle E^x . To prevent the handle from being removed from the spindle e'^x unless the locking member E is in the locked position the socket e^x is preferably provided with a lug or projection e^s which is adapted to engage during the placing of the handle in position in a straight groove d (Fig. 5) in the bracket D^x and during the locking movement of the handle, in a circumferential groove d^x in the inner surface of the said bracket. The shank of the said handle projects laterally from the mounting in such a manner that it occupies a position that prevents the sight F (shown in chain lines in Figs. 6 and 7) from being placed in the holder F' . It will thus be evident that as the handle E^x can be withdrawn from its position on the spindle e'^x only when the locking member E is in the locked position, the sight cannot be placed in its holder and the gun consequently cannot be sighted, when the handle is in place and the locking member is in the unlocked position. This condition of the parts is shown in Figs. 6 and 7.

The herein described form of trunnion block enables the trunnions to be carried right through the side cheeks of the carriage and an extension C^x to be formed on the same for supporting the sight. The aforesaid bush D' in which the trunnion is eccentrically mounted is, in the example shown in Fig. 1, of elliptical shape and has between it and the bearing d' a number of rollers carried in a cage d^2 . In order to adjust the distance of the trunnions from the axis of the vertical training pivot to compensate for lack of balance, each of the trunnion blocks is removed and the elliptical bush D' taken out of position in the trunnion block, turned over so that its forward part occupies a position toward the rear and

is then replaced, when it is obvious that the position of the trunnions will be moved either forward or rearward with respect to the training pivot as required.

What we claim and desire to secure by Letters Patent of the United States is:—

1. In a gun mounting, the combination of the carriage side cheeks, trunnion blocks slidably disposed in longitudinal recesses therein, locking members carried by the trunnion blocks and situated in front of the trunnions which pass through the trunnion blocks, means for moving said members into and out of engagement with slots formed in the side walls of the longitudinal recesses, and sight supporting extensions on the trunnions, said extensions passing through slots in the outer side walls of said recesses for the passage of said extensions when the gun is being housed and replaced in position. 85

2. In a gun mounting, the combination of the carriage side cheeks, trunnion blocks slidably disposed in longitudinal recesses therein, the said recesses being so formed that the forward ends of the trunnion blocks are surrounded by the walls of the recesses, locking members carried by the trunnion blocks and situated in front of the trunnions which pass through the trunnion blocks, means for moving said members into and out of engagement with slots formed in the side walls of the longitudinal recesses, and sight supporting extensions on the trunnions, said extensions passing through slots in the outer side walls of said recesses for the passage of said extensions when the gun is being housed and replaced in position. 95

3. In a gun mounting, the combination of the carriage side cheeks, trunnion blocks slidably disposed in longitudinal recesses therein, rotary locking members carried by the trunnion blocks and situated in front of the trunnions which pass through the trunnion blocks, means for moving said members into and out of engagement with slots formed in the side walls of the longitudinal recesses, and sight supporting extensions on the trunnions, said extensions passing through slots in the outer side walls of said recesses for the passage of said extensions when the gun is being housed and replaced in position. 110

4. In a gun mounting, the combination of the carriage side cheeks, trunnion blocks slidably disposed in longitudinal recesses therein, locking members carried by the trunnion blocks and situated in front of the trunnions which pass through the trunnion blocks, sight supporting extensions on the trunnions, said extensions passing through slots in the outer side walls of said recesses for the passage of said extensions when the gun is being housed and replaced in position, and means carried by the trunnion blocks and situated in front of said exten- 130

sions for moving said members into and out of engagement with slots formed in the side wall of the longitudinal recesses.

5. In a gun mounting, the combination of the carriage side cheeks, trunnion blocks slidably disposed in longitudinal recesses therein, the said recesses being so formed that the forward ends of the trunnion blocks are surrounded by the walls of the recesses, locking members carried by the trunnion blocks and situated in front of the trunnions which pass through the trunnion blocks, sight supporting extensions on the trunnions, said extensions passing through 15 slots in the outer side walls of said recesses for the passage of said extensions when the gun is being housed and replaced in position, and means carried by the trunnion blocks and situated in front of said extensions for moving said members into and out of engagement with slots formed in the side wall of the longitudinal recesses.

6. In a gun mounting, the combination of the carriage side cheeks, trunnion blocks 25 slidably disposed in longitudinal recesses therein, rotary locking members carried by the trunnion blocks and situated in front of the trunnions which pass through the trunnion blocks, sight supporting extensions on 30 the trunnions, said extensions passing through slots in the outer side walls of said recesses for the passage of said extensions when the gun is being housed and replaced in position, handles carried by the trunnion blocks and situated in front of said extensions, and gearing connecting said handles to the rotary locking members.

7. In a gun mounting, the combination of a trunnion block, a locking member for 40 said block, means for moving said member into its engaged and disengaged position, a sight support, and a device forming part of said means and being so positioned in relation to the said support that the sight is pre-

vented from being placed in position when the locking member is in the unlocked condition.

8. In a gun mounting, the combination of a trunnion block, a locking member for said block, an actuating handle for said member, and a sight support so positioned in relation to the handle that the latter prevents the sight from being placed in position when the locking member is in the unlocked condition.

9. In a gun mounting, the combination with the side cheeks of the carriage, of a trunnion block mounted therein, a bush in which one of the gun trunnions is eccentrically mounted, and means for enabling the 60 said bush after having been withdrawn from the trunnion block and inverted to be replaced in the block with the gun trunnion in a different position relatively to the side cheeks.

10. In a gun mounting, the combination with the side cheeks of the carriage, of a trunnion block mounted therein, and an elliptically shaped bush in which one of the trunnions is mounted, said block having an 70 elliptically shaped recess to receive the bush in one or other of two positions.

11. In a gun mounting, the combination with the side cheeks of the carriage, of a trunnion block mounted therein, an elliptically shaped bush in which one of the trunnions is mounted, said block having an elliptically shaped recess to receive the bush in 75 one or other of two positions, and a cage of rollers interposed between said bush and the 80 trunnion block.

In testimony whereof we affix our signatures in presence of two witnesses.

ARTHUR TREVOR DAWSON.
GEORGE THOMAS BUCKHAM.
